UNITED STATES PATENT OFFICE.

HERBERT G. BEEDE, OF PAWTUCKET, RHODE ISLAND.

DRIVE MECHANISM FOR TWISTING AND SPINNING FRAMES.

Application filed March 29, 1923. Serial No. 628,532.

To all whom it may concern:

Be it known that I, HERBERT G. BEEDE, a citizen of the United States of America, and resident of Pawtucket, in the county of Providence and State of Rhode Island, have invented new and useful Improvements in Drive Mechanism for Twisting and Spinning Frames, Case B, of which the following is a specification.

This invention relates to twisting and spinning machines and more particularly to spindle driving mechanism therefor. The spindles of such machines are usually driven by means of endless bands which pass about a drum or driving pulley. To secure smoothness of operation as well as to prevent loss of time in replacing worn or broken bands it is desirable to employ integrally continuous or jointless bands, preferably made by a weaving or similar operation. Such bands cannot be applied to the machine as usually arranged and the object of the present invention is to provide an arrangement of parts which makes possible the employment of such continuous and jointless driving bands.

In the accompanying drawings a preferred arrangement is illustrated by way of example, together with certain modifications thereof.

In the drawings:

Fig. 1 is a fragmentary plan view of a spinning or twisting frame of usual construction having the present invention applied thereto;

Fig. 2 is a vertical cross section on a line such as 2—2 of Fig. 1;

Fig. 3 is a fragmentary vertical section on the line 3—3 of Fig. 2, certain parts being omitted;

Fig. 4 is a plan and Fig. 5 is an end elevation showing diagrammatically a modified arrangement;

Figs. 6 and 7 are plan and end elevations respectively showing diagrammatically a further modification;

Fig. 8 is a fragmentary plan view, similar to Fig. 1, but illustrating a further modification;

Fig. 9 is a vertical cross section on the line 9—9 of Fig. 8; and

Figs. 10 and 11 are diagrammatic end elevations illustrating further modifications of the belt tensioning means.

Referring to Figs. 1, 2 and 3, the side rails of the spinning or twisting frame are indi-

cated at 1, 2, respectively. These side rails support series of spindles, certain of which are indicated by way of example at 3, 4, 5, 6; 3^b, 4^b, 5^b, 6^b, respectively. The several spindles are provided with whirls 7 in the usual manner. Transverse members 8 are arranged at intervals longitudinally of the frame, and support spaced brackets 9, 10. The brackets 9 are provided with journal bearings for a longitudinally extending shaft 11, while the brackets 10 support journal bearings for a shaft 12. The shafts 11 and 12 are provided with pulleys 13, 14 at a convenient point, preferably adjacent to one end of the machine, and a belt 15 engages these pulleys and compels them to rotate in the same direction. The shaft 12 is also furnished with a pulley 16 for a drive belt, (not shown) receiving its power from any suitable source. Spindle driving pulleys such as 11^a, 12^a, 11^b, 12^b are mounted upon the shafts 11 and 12, the pulleys 11^a and 12^a turning substantially in the plane defined by spindles 3 and 5, while pulleys 11^b and 12^b turn in a plane defined by spindles 3^b, 5^b, etc.

A bracket 17 is secured to each of the several transverse members 8 and these brackets are furnished with vertical guide openings for the reception of slide plates 18. Each of these plates is provided with a bracket 19 at its upper end which carries a bearing 20 for the shaft 21 of a pulley such as 22 or 22^b. Integrally continuous endless bands such as 23, 23^b, partially encircle spindle whirls at opposite sides of the machine, one run of each of such bands extending directly across from a spindle on one side to a spindle on the other while the other run engages one of the pulleys 11^a or 11^b.

For example the band 23 contacts with the pulley 11^a at the point 24 then passes beneath the pulleys 22 and 25, and thence over the pulley 12^a as indicated at 26. Preferably each band partially encircles or embraces the whirls of two spindles such as 3 and 4 on one side of the machine and corresponding spindles 5 and 6 on the other side of the machine, a single band thus serving to drive four spindles, although it is contemplated that the band may embrace but a single whirl at either side of the machine if desired. Each band is made of such a length that when positioned as above described, the weight of the pulley 22 and the slide plate 18 is supported by the band so that the

band is properly tensioned and held in driving contact with the peripheral surfaces of the drive pulleys. In a similar manner each group of spindles of the frame may be driven.

In placing the band in position it is merely necessary to pass it over the spindles at opposite sides of the machine and then by lifting the guide pulley to pass one run of the band beneath such pulley so that the weight of the pulley is supported by the band. When the band requires replacement, the guide pulley 22 is lifted slightly and the band may be removed without difficulty. It is thus possible to employ bands which are woven continuously and which may be put in position without splicing.

The arrangement shown in Figs. 4 and 5 is generally similar to that above described. In this case the spindles 31, 32 are driven by a band 35, one run of which passes over the adjacent surfaces of drive pulleys 36 and 37 and under a tension pulley 38. The tension pulley is arranged substantially below the pulleys 36 and 37 and may be guided in the same manner as the pulley 22 above described or in any other suitable way.

In Figs. 6 and 7 a further modification is shown in which the spindles 41, 42, 43 and 44 are driven by means of an endless band 45, one run of which engages the under surface of drive pulleys 46, 47 and then passes over a tension or guide pulley 48 intermediate the pulleys 46 and 47. In this case the pulley 48 is mounted on a stub shaft 49 carried by a link 50 which in turn is supported upon one arm of a lever 51 fulcrumed at 52 and whose other arm supports a counterbalance weight 53 by means of a link 54.

In Figs. 8 and 9 a modified arrangement is shown in which the side frame members of the machine are designated 101, 102 respectively. Upon these side frames spindles 300, 500 respectively are mounted in usual manner. Longitudinally extending drive shafts 111, 112 are journaled in suitable supports carried by the frame and upon these drive shafts pulleys 111^a, 112^a respectively are arranged corresponding to each pair of oppositely disposed spindles, the pulleys being disposed substantially in the vertical planes defined by such pairs of spindles. A bracket 509 corresponding to each pair of pulleys 111^a, 112^a is secured upon longitudinally extending rods or bars 80 and a lever 510 is pivotally mounted at the point 520 of each of said brackets. The free extremities of these levers are weighted in any suitable manner as indicated at 530. Each lever is provided with a stub shaft 210 upon which a guide pulley 222 is mounted. Driving belts 23^a partially encircle the spindle whirl of each spindle of a pair, one run of the belt extending directly across from one spindle whirl to the other while the other

run passes downwardly over the pulley 111^a beneath the guide pulley 222 and over the pulley 112^a. The guide pulley 222 thus serves to tension the belt and keep it in operative relationship to the driving pulleys and 70 the spindle whirs. With this arrangement it is possible as in the previous constructions to apply an endless belt to the spindles and driving pulleys without the necessity of joining the ends of the belt after it has been 75 passed about the several operative elements. In Fig. 10 a further modification is shown in which the driving pulleys 111^b and 112^b are indicated in dotted lines and the guide pulley 222^a is shown as journaled upon a 80 stub shaft 210^a carried at the upper end of a link 81 pivoted at its lower end at the point 82 to the lever 510^a. This lever is fulcrumed at the point 520^a upon any suitable bracket, not shown, and is preferably weighted at its free extremity as indicated at 530^a. With this arrangement the pull upon the belt is exerted in a substantially vertical direction without lateral component. 85

In Fig. 11 a further modification is shown in which the tension of guide pulley 222^b is shown as journaled upon a stub shaft carried by the upper end of a link 84 pivoted at an intermediate point 85 to the lever 510^b. This lever is fulcrumed at the point 520^b and may be counterweighted at its free extremity as shown at 530^b. The link 84 projects downwardly beyond the pivot point 85 and is pivotally secured at 86 to a second lever 87 parallel to the lever 510^b and journaled at the point 88. With this arrangement of parallel levers the guide pulley is constrained to move in a predetermined path without necessitating the employment of a fixed guideway. 90

In either of the arrangements described the axis of the tension pulley is disposed in a vertical plane intermediate the vertical planes of the shafts of the drive pulleys so that its acts simultaneously to press the driving band into contact with the peripheral surfaces of each of the drive pulleys. It is also clear that by employing mechanism such as described it is possible to apply an integrally continuous endless band or to remove it without difficulty or loss of time. Such bands provide a much smoother and more uniform means for driving the spindles than the usual bands having joints, while the application of bands of this kind can be performed much more expeditiously than when the bands must be spliced as is the usual practice. While certain specific arrangements have been shown herein as desirable, it is evident that other and equivalent arrangements may well be employed without departing from the spirit of the present invention. 110

I claim:

In a machine of the class described hav-

ing a pair of spaced parallel side rails, transverse members rigidly connecting said rails, a row of spindles carried by each rail, a pair of spaced brackets carried by each 5 of said transverse members, a pair of longitudinal drive shafts turning in the same direction in bearings carried by the brackets, and a drive pulley mounted upon each shaft, said pulleys being disposed in the same 10 plane, in combination, an auxiliary bracket mounted upon one of said transverse members intermediate the bearing brackets supported by said transverse member, said auxiliary bracket having a portion offset 15 from the transverse member and provided with an elongate vertical guideway disposed midway between the drive shafts, a slide plate freely slidable vertically in said

guideway, a bearing supported by the plate, a shaft in the bearing, a tension pulley 20 mounted on the shaft, said pulley being disposed in the plane of the pulleys upon the drive shaft, and an endless integrally continuous band partially encircling a spindle of each row of spindles, both runs 25 of said band being disposed above said drive shafts, one run of the band engaging the upper portions of both drive pulleys, said run also passing below the tension pulley and supporting the weight of said pulley and the vertically sliding plate. 30

Signed by me at Pawtucket, Rhode Island, this twenty seventh day of March 1923.

HERBERT G. BEEDE.
